UNITED STATES PATENT OFFICE.

HEINRICH EBERHARD, OF BASEL, SWITZERLAND.

NON-REFILLABLE BOTTLE.

1,119,257.

Specification of Letters Patent.

Patented Dec. 1, 1914.

Application filed February 25, 1913. Serial No. 750,555.

To all whom it may concern:

Be it known that I, HEINRICH EBERHARD, a citizen of the Swiss Republic, residing at Basel, in Switzerland, have invented certain new and useful Improvements in Non-Refillable Bottles, of which the following is a specification.

This invention relates to non-refillable bottles of the type in which a buoyant valve has a seat at or near the base of the bottle-neck and is held down on the said seat by a ball weight, when the bottle is upright. When a bottle of this type is tilted for pouring out liquid, the ball weight rolls away from the valve, and is then stopped by a guard in the bottle-neck, and the liquid is able to displace the valve from its seat and flow out. It has been found in connection with bottles of this type that the valve (usually a hollow, tapered body) is liable to stick, so that frequently the bottle has to be shaken, after tilting it, in order to remove the valve from its seat.

The object of the invention is to obviate this disadvantage and provide an auxiliary device whereby the valve is quickly removed from its seat when the bottle has been tilted and ball weight has rolled away. To this end I place in the enlarged, hollow upper part or head of the valve a movable tumbling weight which, when the ball has rolled away, tumbles over in the valve head, and sharply strikes the roof of the head, the impact assisting in displacing the valve from its seat.

The invention is illustrated in the accompanying drawing, in which—

Figure 1 is a sectional view of the upper part of the bottle, showing the same in upright position. Fig. 2 is a similar section, showing the bottle tilted.

In the drawing, *a* designates the bottle-neck, which has an internal annular groove *b* about midway between its ends. Below this groove the neck is somewhat enlarged to form a chamber *c*, the junction of which with the body of the bottle forms a valve-seat *c'*. The chamber *c* contains a ball-weight *d*, which normally rests on a valve *e* closing the *c* and surrounded by the seat *c'*. The valve *e* has a comparatively large, hollow base *e'* and a tapered stem *e''*, and rests on its seat by means of the shoulder formed where the head joins the stem. The extent to which the ball can roll along the neck is limited at one end by the valve *e* and at the

other end by a guard *f* fixed in the neck. The head of the valve is considerably larger than the stem *e'*, and its weight comprises about two thirds of the total weight of the valve. The head incloses a tumbling weight *g*, in the form of a disk which exceeds in diameter the diameter of the constricted lower part of the head, but is of smaller diameter than the concavo-convex roof of the head. It will be understood that the weight *g* is not sufficiently heavy to destroy the buoyancy of the valve.

The guard *f* in the neck of the bottle has bent channels *f'* which allow the liquid to flow through the neck. As shown in Fig. 2, one limb of each of these channels is longer than the other, so that the guard forms an effective obstruction to the insertion of a helically bent wire whereby the valve could be tampered with. The guard, which can slide into the neck from the top, is fixed by means of a short metal or glass rod *k* engaging the groove *b*. This rod is slidable in a transverse channel in the guard, and abuts in this channel against a plug *h* of elastic cork, so that the rod can be pushed back in the channel, to allow the guard to enter the neck, but is thrust outward to engage the groove *b* when the rod arrives opposite the said groove. The connection thus made between the guard and the neck can only be unmade by breaking the neck.

I may construct the valve *e* of aluminium or other light material, the ball *d* being of glass, china or other suitable material.

The action of the device will be clear from the drawing. When the bottle is tilted, as shown in Fig. 2, the ball *d* rolls away from the valve *e* toward the guard *f*, and the weight *g* tilts over within the head of the valve and tumbles against the roof of the head, thus delivering a blow which assists in removing the valve from its seat.

It will be clear that the bottle cannot be re-filled while held in a tilted position, because liquid introduced into the neck will lift the valve to its seat.

What I claim as my invention and desire to secure by Letters Patent of the United States is:

In a bottle having a neck the combination of a valve-seat in said neck; a buoyant valve comprising a hollow head and a stem joined to said head, said valve-head fitting on said seat, but being capable of rocking in all directions thereof, a ball-weight in said neck

above said valve; means retaining said ball-weight in said neck but allowing limited movement of said weight between said valve and the mouth of said neck; and a flat tumbling weight in said hollow valve head, arranged to tumble against the roof of said head when the bottle is inverted, whereby said valve head is knocked off its seat; said retaining means and ball-weight preventing

complete withdrawal of the valve stem 10 from the orifice within said valve seat.

In witness whereof I have signed this specification in the presence of two witnesses.

HEINRICH EBERHARD.
